VACUUM POLISHING LATHE

Harold E. Crozier, Hawthorne, Calif.

Application November 24, 1944, Serial No. 565,038

10 Claims. (Cl. 51—235)

My invention relates to a vacuum polishing lathe and has for its principal object, to provide simple, convenient and highly effective means for accomplishing the rapid and economic polishing of small structural parts of various shapes and sizes, and which parts, while being polished, are held by vacuum on an adaptor or fixture and the latter being carried on the end of a shaft capable of being driven at high speeds.

A further object of my invention is, to provide a polishing lathe of the character referred to, having a simple and effective vacuum pump for exhausting the air from the adaptor or fixture which receives the work to be polished, which pump includes a rotor mounted on the high speed shaft, with a series of radial vanes carried by said rotor and the latter and said vanes, being eccentrically arranged within the pump chamber.

A further object of my invention is, to provide simple and efficient means for controlling the operation of the high speed shaft which carries the work receiving fixture and drives the vacuum pump.

With the foregoing and other objects in view, my invention consists in certain novel features of construction and arrangement of parts which will be hereinafter more fully described and claimed and illustrated in the accompanying drawing, in which:

Fig. 1 is a side elevational view of my vacuum polishing lathe with the end portions thereof in vertical section.

Fig. 2 is a detail section taken on the line 2—2 of Fig. 1.

Fig. 3 is an elevational view partly in section, and showing an electric switch operating means.

Fig. 4 is a plan view of the switch operating device.

Fig. 5 is a perspective view of a spring used in the switch operating device.

Fig. 6 is an enlarged cross section taken on the line 6—6 of Fig. 1.

Fig. 7 is a perspective view of a modified form of the vanes used in the vacuum pump.

Referring by numerals to the accompanying drawing, which illustrates a preferred embodiment of my invention, 10 designates a housing through which passes a shaft 11, carrying an armature 12 and the latter operating within a conventional field 13.

Shaft 11 operates in anti-friction bearings 14 in the end portions of housing 10 and extending entirely through said shaft is an axial duct 15. Removably positioned on the forward end of shaft 11 is a disc like fixture or adaptor 16, in the front

face of which is seated a rubber ring 17, against which the piece such as P, which is to be polished, is positioned.

An air tight joint is formed between the ring 17 and the piece positioned against same and thus said piece is firmly held against said ring, by the partial vacuum produced in duct 15, and in the chamber between disc 16 and the work, as will be hereinafter more fully described. Suitably secured to shaft 11 adjacent disc 16 is a collar 18 provided on its inner end with a flange 19, and loosely mounted on said collar is a brake ring 20, carrying a facing 21 of friction producing material which is adapted to contact flange 19.

The outer face of ring 20 is positioned adjacent the inner face of a ring 22, which is secured to the end of motor housing 10 and formed in the inner face of said ring 22 is a plurality, preferably three, inclined cam surfaces 23, against which bear balls 24, loosely arranged in recesses 25 in the outer face of brake ring 20.

A lever handle 26 seated in brake ring 20, projects radially outward through a slot 27 in housing 10, and when said handle is moved rearwardly, the brake ring is partially rotated so as to cause balls 24 to ride up the cams 23 and thereby shift ring 20 inwardly so that facing 21 frictionally engages flange 19, thereby exerting braking effort on shaft 11, tending to cause same to cease rotating.

Reverse movement of lever 26 moves balls 24 down the cams, thus removing pressure on the brake ring.

A box 28 which may be mounted on the side of motor housing, below hand lever 26 contains the switch which controls the line conductors to and from the motor and said switch being actuated by a conventional toggle arm 27.

Seated in brake ring 20 and projecting through a slot 29 in housing 10, is a short arm 30 and connecting same with toggle arm 27 is a spring 31, having one or more intermediate coils 32 (see Fig. 5).

When hand lever is positioned so that balls 24 are at the lower ends of cams 23, the brake is released and arm 30 is positioned so that, through spring 31, switch arm 27 is in switch opening position, and thus, when said lever is moved so as to apply the brake, the switch arm will be snapped into position to open the switch in box 28, thereby cutting off the current supply to the motor (see Figs. 3 and 4). Formed integral with or fixed to the opposite end of housing 10 is a circular wall 33, providing a pump chamber 34, which is eccentric with respect to the axis of

shaft 11. The outer end of this chamber is closed by a removable plate 35 and formed on the external faces of said wall and plate are heat disseminating fins 33^a and 35^a respectively.

The reduced end 11^a of shaft 11 projects eccentrically into chamber 34 and concentrically mounted thereon is the cylindrical body of a pump rotor 36, provided with a plurality of radially disposed slots 37, within which are arranged for sliding movement, vanes 38, the bottom edges of which, when the pump is in operation, bear on the inner face of wall 33. The bottom faces of the slots 37 are curved lengthwise and the bottom faces of vanes 38 are correspondingly curved. Formed in the rear faces, in the direction of rotation of the pump rotor, are ducts 39, which extend from the bottoms of said vanes to points near the top faces thereof.

If desired, the ducts just described may take the form of holes such as 40 drilled in the vanes (see Fig. 7). The curved bottoms of the slots 37 are connected by short ducts 41, with circumferential grooves 42 in the periphery of the reduced end of shaft 11 on which the rotor 36 is mounted and apertures 43 are formed in the shaft between said grooves 42 and the axial duct 15.

Formed through the end wall of the motor housing and establishing communication between the compression side of chamber 34 and the interior of the motor housing are ports 44 which deliver jets of air compressed in the pump chamber, directly against and over the armature of the motor thus cooling same.

In operation, the actuation of hand lever 26, to move balls to the lower ends of cams 23, releases brake 20, 21 and at the same time arm 30 through spring 31 shifts switch lever into position so as to close the circuit to the motor and thereby start same.

The operation of rotor 36 and vanes 38 acts to exhaust air through duct 15 in the motor shaft which air after being compressed in chamber 34, discharges through ports 44 and passes over the armature with cooling effect. When an article to be polished is placed against ring 17, the partial vacuum in the chamber between disc 16 and said article, will by suction anchor the latter to the adapter so that said article is rotated at motor speed during the polishing operation.

Reverse movement of lever 22, sets the brake against flange 22 and at the same time, switch lever 27 is actuated to open the motor circuit.

Thus it will be seen that I have provided a vacuum polishing lathe which is simple in structure, inexpensive of manufacture and very effective in performing the functions for which it is intended.

It will be understood that minor changes in the size, form and construction of the various parts of my improved vacuum polishing lathe may be made and substituted for those herein shown and described without departing from the spirit of the invention, the scope of which is set forth in the appended claims.

I claim as my invention:

1. In a vacuum polishing lathe, a motor driven shaft having a longitudinally disposed duct, a work receiving fixture carried by one end of said shaft, a flexible member carried by said fixture and adapted to be engaged by the piece to be polished and means actuated by said motor shaft for reducing the pressure in the duct in said shaft and in the space between said fixture and the piece applied thereto.
2. A vacuum polishing lathe as set forth in claim 1 and with manually operable means for controlling the operation of said motor driven shaft.
3. In a vacuum polishing lathe, a shaft having a longitudinal duct, means for rotating said shaft, a work supporting fixture on the end of said shaft and a continuous flexible flange on said fixture.
4. A vacuum polishing lathe as set forth in claim 3, with means actuated by said shaft for exhausting air through the duct in said shaft and from the space between said fixture and the piece applied to said flexible flange.
5. A vacuum polishing lathe as set forth in claim 3, with means actuated by said shaft for exhausting the air through the duct in said shaft and from the space between said fixture and the piece applied to said flexible flange and manually operable means for controlling the operation of said shaft.
6. In a vacuum polishing lathe, an electric motor, the shaft of which is provided with a longitudinal duct, a work receiving fixture carried by one end of said shaft, the suction side of which pump has communication with the duct in said shaft and a manually operable brake for controlling the operation of said shaft.
7. A vacuum polishing lathe as set forth in claim 6 with a switch for controlling flow of current to said motor and operating connections between said brake and said switch whereby current flow to the motor is cut off when the brake is applied and current flow to the motor established when the brake is released.
8. A vacuum polishing lathe as set forth in claim 6, and with means for directing jets of air from the compression side of said vacuum pump toward and against the armature of said electric motor.
9. In a vacuum polishing lathe the combination with a driven shaft having a longitudinal duct, of a work receiving fixture on one end of said shaft, a continuous elastic seat on said fixture for an article to be polished, the chamber between said fixture and the piece applied to said flange having communication with the duct in said shaft and means for establishing a partial vacuum in said duct and space.
10. The combination as set forth in claim 9 and with manually operable means for controlling the operation of said shaft.
